Henry Frederick Meyer,

UNITED STATES PATENT OFFICE.

HENRY FREDERICK MEYER, OF WILL, ILLINOIS.

POTATO-DIGGER.

SPECIFICATION forming part of Letters Patent No. 368,482, dated August 16, 1887.

Application filed March 28, 1887. Serial No. 232,665. (No model.)

To all whom it may concern:

Be it known that I, HENRY FREDERICK MEYER, a citizen of the Province of Hanover, in the Empire of Germany, residing in the town-
ship of Will, in the county of Will and State of Illinois, have invented certain new and useful Improvements in Potato-Diggers, of which the following is a specification, reference being had thereto to the accompanying drawings.
10 This invention relates to certain improvements in potato-diggers, the construction and operation of which are fully set forth and explained in the following specification and claims, reference being had to the accompanying drawings and the figures and letters of reference thereon, which form a part of this specification, in which—

Figure 1 is a side elevation of the machine. Fig. 2 is a horizontal cross-sectional view of 20 the elevator of the machine on line 1, Fig. 1, looking down upon the shovel, and the mechanism for operating the elevator-apron. Fig. 3 is a top plan view of the machine. Fig. 4 is a central vertical cross-sectional view of the 25 sifter of the machine. Fig. 5 is a rear view of the machine, showing the sifter and mechanism for operating it, other parts being broken away; and Fig. 6 is a front view of the forward part of the machine, showing the adjustable bar for holding the front end of the elevator-tongues, other parts being broken away.

Referring to the drawings, A and A' represent the axles, and W W' are traveling wheels 35 on said axles, which axles and wheels support and transport the machine.

B B are the bed-sills, the forward ends of which rest on the bolster A² on the front axle, A, and the rear ends of said sills rest directly 40 on the rear axle, A'.

Q is a reach connecting the two axles, the rear part of which reach is forked or branched, so that the working parts of the machine may be located between its parts, as shown in Fig. 3. 45 P P are a pair of upright posts standing one on each sill B, about central in the machine, and P' P' are a pair of posts standing one on each sill, near its rear end, as shown in Figs. 1 and 5, (one of the posts P being hidden in Fig. 1 by its fellow post.)

B' B' are beams respectively located directly

above sills B B, and connecting, respectively, the posts P P'.

B² is a cross-beam connecting the beams B' B' near the upper ends of posts P P, and B³ is 55 a cross-beam connecting the upper ends of posts P' P'.

a a are a pair of short posts respectively bolted to the bolster A², and are connected at their top by a cross-bar. 60

a² is a cross-bar adjustably secured to said posts a a by means of pins or bolts a' a', passing through holes in said cross-bar and posts, as shown in Figs. 1 and 6.

E is an adjustable elevator carrying an end-less-apron carrier, F, supported on proper rollers, R' R², one at each end, which apron is provided with equidistant rows of teeth t. 65

D² D³ are a pair of tongues respectively secured at their rear ends to the outer sides of 70 the elevator E, near its lower end, and united at their forward ends, and resting on the adjustable cross-bar a². These tongues thus supported on the cross-bar a² support the lower forward part of the elevator E and the plow 75 S, which is secured to said elevator, and vertically adjust the point of said plow by means of elevating and lowering said cross-bar a², as stated.

As a means for elevating and holding ele- 80 vated from the ground the elevator and its parts, the machine is provided with a lever, L, which is fulcrumed in post H, standing on cross-beam B³, by means of pin V, passing through slot L' in said lever, its inner end being pivoted to cross-rod I, passing transversely through the upper end of the elevator-frame. (See Figs. 1 and 2.)

J is a segment secured to said post H, and is provided with hooks J', under which to hook 90 the outer end of lever L when it is desired to hold the elevator and its parts from the ground. V' is a row of holes in post H, for changing pin V to vertically adjust said lever.

D⁴ is a draft-chain connecting the forward 95 axle, A, with a cross-bar connecting the tongues D³ about their center, as shown in Figs. 1 and 2, by means of which draft-chain the elevator and its parts are drawn.

S is a plow having a central point and sides, 100 and is secured to the elevator E at its front lower end, as shown in Figs. 1 and 2.

R' is the lower roller of the elevator, and carries the lower end of the endless apron F, and R is a traveling roller properly boxed in and between the two rearwardly-extending arms E' E' of the rear lower part of the elevator E, as shown in Figs. 1 and 2.

The shafts of rollers R R' are respectively provided with the spur-gears G and G³, connected by means of the idler-gears G' G², and 10 E² is a guard for covering and protecting said gear mechanism to exclude vines and dirt. The endless apron F is driven by means of traveling roller R through the medium of said gearing, which drives roller R'.

15 D is a shaker located at the rear upper end of the elevator to catch its discharged contents, and is suspended at its front end from the beams B' B' by means of the links d d, and at its rear end from the cross-bar B³ by means of 20 the bail d' and the rod or strap d'', passing through said cross-bar, and having the row of pin-holes and pin h, for vertically adjusting the rear end of the shaker to properly incline its bars. (See Figs. 1 and 5.) The said shaker 25 is rectangular in form, and is provided with two sets of longitudinally-arranged bars, e and e', forming sifters for separating the dirt and vines from the tubers. The upper bars, e, are arranged farther apart than the lower bars, e', 30 and are designed more particularly for separating the vines and larger lumps of earth from the tubers and discharging the sifted-out matter from the rear opening in the shaker to the spout D', which discharges it at one side of the machine. (See Figs. 1, 3, and 5.) The lower 35 bars, e', are nearer together and are intended to separate the tubers from the earth, which falls through between said bars, and the tubers roll along out of the shaker D and fall in spout 40 D², which conducts them to a basket resting on the platform M, secured to the rear under side of sills B B. (See Figs. 1, 3, and 5.) Said shaker D is caused to vibrate through the medium of quadrant O, pivoted to post P', link O', 45 pitman C², and crank-disk C', having a sprocket-chain, C, connecting said mechanism with sprocket-wheel W² on wheel W'. (See Figs. 1, 3, and 5.)

Z Z are a pair of levers arranged one on 50 either side of the upper end of elevator E, and pivoted at their inner forward end to the cross-bar B², and their rear ends rest on cross-bar B³, and are adjustably attached thereto by means of pins g' g', passing through said levers 55 and cross-bar B³. (See Figs. 1 and 3.) Said cross-bar B³ is provided with the row of pin-holes g, for the purpose of permitting said elevator to be laterally adjusted by means of moving said levers laterally and securing them adjusted by means of moving said pins g' in said 60 row of holes g.

N is a driver's seat secured on cross-bar B².

N' is a foot-board bracketed to posts P P, and T is a tongue secured to the front axle-hounds, to which tongue the team for propelling the machine is attached.

The elevator and its endless-apron carrier have no other connection with the frame of the machine than through the medium of the tongues D³ D³ and levers L and Z Z. The 70 depth to which it is desired to permit the plow to enter the ground is regulated by means of elevating and lowering the outer ends of the tongues D³ D³.

Lateral adjustment is given the upper end 75 of the elevator to hold the elevator in a vertical position when the machine is working on a side hill or uneven ground, and the lever L furnishes means to elevate the plow entirely 80 out of the ground, so the machine may be transported from place to place. The slot in said lever permits forward and backward motion of the upper end of the elevator when in operation.

In operation the plow S plows up the hills 85 and carries them back to the endless-apron carrier F, the teeth of which carry it up and deposit it in the shaker D, which sifts the tubers out, as described. Much of the earth is sifted 90 out from the vines and tubers as the hill is being carried up the elevator by the carrier and falls out at the rear of the plow between it and the carrier.

When the machine is in operation, the elevator and its carrier rest entirely on the traveling roller R and tongues D³ D³, and the carrier is operated entirely by the said traveling roller, so that the plow is not controlled or disturbed by means of the truck-wheels of the machine passing over inequalities of the 100 ground.

Having thus described my invention, what I claim as new, and desire to secure by Letters Patent, is as follows, to wit:

1. In the potato-digger described, and in 105 combination with its frame, the elevator E, having the endless toothed apron-carrier F, adjustable tongues D³ D³, secured to the sides of said elevator and resting on cross-bar a², slotted lever L, draft-chain D⁴, traveling roller 110 R, spur-gears G G' G² G³, and plow S, substantially as and for the purpose set forth.

2. In the potato-digger described, and in 115 combination with the frame, the elevator E, and the means for adjustably attaching said elevator to said frame, and the levers Z Z, for laterally adjusting said elevator, substantially as and for the purpose set forth.

3. In the potato-digger described, the elevator E, having the toothed endless-apron carrier F, plow S, traveling roller R, and spur-gears G G' G² G³, in combination with the 120 tongues D³ D³, slotted lever L, and levers Z Z, whereby the said elevator is vertically and laterally adjusted, substantially as and for the 125 purpose set forth.

4. In a potato-digger, an elevator provided with an endless toothed apron carrier, and a plow for conducting the tubers to the carrier, and having a traveling roller or wheel for 130 maintaining the weight of and driving its elevating mechanism, in combination with the

means, substantially as described, for adjustably attaching the elevator to the machine-frame in such manner that its operation is uncontrolled by the truck-wheels of the machine passing over inequalities of the ground, substantially as specified.

5. In the potato-digger described, the levers ZZ, having their inner ends respectively pivoted to cross-bar B², and having their outer ends adapted to be laterally adjusted, in combination with the elevator E, substantially as and for the purpose set forth.

6. In the potato-digger described, the tongues D³ D⁴, in combination with the elevator E, draft-chain D⁴, and means, substantially as shown, for vertically adjusting said tongues, as and for the purpose set forth.

7. In the potato-digger described, and in combination with the elevator E, tongues D³ D⁴, and segment J, having the hooks J', the

lever L, having the slot L', as and for the purpose set forth.

8. In a potato-digger, in combination with a frame mounted on traveling wheels and carrying a vibrating sifter operated by means of one of the traveling wheels through the medium of pulleys and a belt and crank mechanism, substantially as described, an endless toothed carrier elevator independently mounted on a traveling roller or wheels geared to and arranged to operate said endless-apron carrier, and having a guiding-tongue resting upon an adjustable support of said frame, and transported, together with said frame, by means of a draft chain or bar connecting them, as specified.

HENRY FREDERICK MEYER.
